 a corporation of New York

Application April 6, 1945, Serial No. 586,953

7 Claims. (Cl. 308—230)

1

This invention relates to the manufacture of quartz oscillator plates and has for its object certain improvements in apparatus employed in lapping blank oscillator plates.

In my co-pending application Serial No. 586,952, filed April 6, 1945, I have disclosed and claimed a method of and apparatus for lapping blank oscillator plates in accordance with which the plates are lapped between two superposed lapping heads, the lower head being rotated and the upper head being held substantially stationary. The lower lapping head is suitably connected to a spindle supported in a non-rotating sleeve, with anti-friction bearings disposed between the spindle and the sleeve. A power-driven carrier-disc is disposed between the two lapping heads. The disc is provided with a plurality of spaced openings, in each of which is placed a blank oscillator plate.

During the lapping operation, the blank plates progressively follow an exceedingly tortuous path between and across the lapping surfaces of the lapping heads, while a generous supply of abrasive grit suspended in a suitable liquid vehicle, such as oil, is fed to the blank plates. Spattering and over-running of some of the abrasive grit on the apparatus are unavoidable and some of it finds its way quickly to the bearing or bearing disposed between the spindle and the sleeve, with resultant damage thereto. This necessitates a shut-down of the whole apparatus to clean, repair, or replace the affected bearing or bearings.

As a result of my investigations, I have discovered that an apparatus may be provided which prevents passage of the abrasive grit to the spindle bearings of the lower lapping head and thus overcomes the serious disadvantages outlined above.

In accordance with the invention, the apparatus comprises a rotatable spindle connectible with a source of power, a sleeve mounted about the spindle, securing means to prevent rotation of the sleeve, and a bearing between the sleeve and spindle. A bushing is rotatably secured to the spindle at one end of the sleeve and a bearing-shield is disposed exteriorly of and about the same end of the sleeve and a portion of the bushing. A nut is rotatably secured to the bushing and bearing-shield to provide a barrier against passage of foreign particles through the end of the sleeve to the bearing.

These and other features of the invention will be better understood by referring to the accompanying drawing, taken in conjunction with the following description, in which the single figure

2

is a sectional view of the lower portion of an apparatus for lapping blank oscillator plates and which illustrates a practice of the invention.

The apparatus comprises a base only the upper wall 10 of which is shown. The base in turn supports a lower spindle 11, to the lower end of which is secured a variable speed pulley 12 connectible with a source of power (not shown). The spindle extends vertically through a bearing securing collar 13, a bearing sleeve 14, a sleeve support 15, a bushing 26 and into a support collar 17. Bearing securing collar 13 is threaded into the internally threaded lower end portion of the sleeve 14. A lower thrust bearing 18 is mounted about spindle 11 within sleeve 14. Sleeve support 15 is secured to sleeve 14 by a set screw 19. At its upper end the sleeve support 14 includes a radially extending annular flange 20 resting upon the upper side of wall 10 and is secured thereto by a plurality of screws 21. An upper thrust bearing 22 is mounted about spindle 11 within sleeve 14.

To prevent ingress of abrasive material or other foreign particles, the upper portion of sleeve 14 is covered with a bearing-shield 23 fitting loosely about the sleeve. The upper portion of the bearing-shield is partly closed by an annular internally threaded portion 24 disposed on the outwardly extending annular shoulder portion 25 at the lower end of a threaded bushing 26 which is secured to spindle 11 by a set screw 27. A nut 28 is screwed onto the threaded bushing and bears downwardly on annular portion 24 to assure a tight fit. As shown, the outwardly extending annular shoulder portion 25 of the bushing 26 fits within the upper end of sleeve 14, immediately adjacent bearing 22.

At its upper end spindle 11 includes a tapered portion 30 having a wedge fit in the tapered socket of the support collar 17. The lower portion of the support collar is thus located directly above lock nut 28 and the threaded bushing 26. The collar 17 includes a radially extending upper flange 31 fitting into a centrally recessed portion of a horizontally disposed support 32 and is secured thereto by means of a plurality of screws 33. A lower rotating lapping head 35 is secured to horizontal support 32 by means of a plurality of spaced screws 36.

An upper lapping head 40 is disposed directly above the lower lapping head and is held in a substantially stationary position by mean not shown. Both lapping heads are annular in shape, being provided with aligned openings 41 and 42. A plurality of funnel-shaped wells 43 extends

through the upper lapping head to receive a grit suspension and feed it into the space between the lapping heads.

A carrier-disc 45 is disposed between the two lapping heads, being provided with a fixed hub 46 secured thereto by a lock-nut 47. The disc is operatively connected to a source of power, not shown, by means of an upper spindle 48 movable up or down by a quill 50 held thereon by a collar 51. The lower end of the upper spindle terminates in a crank arm 52 secured thereto by a set screw 53. A pin 54 is carried by the far end of the crank arm and is provided with a hub 55. The free end of the pin 54 is adapted to fit loosely in hub 46 of the carrier-disc.

As more fully described in the above-mentioned copending applications, with lapping blank oscillator plates confined in carrier-disc 45, lower lapping head 35 is rapidly rotated in one direction and crank arm 52 is rotated less rapidly in the opposite direction while a suspension of abrasive grit is fed through wells 43 to the blank plates. If, any of the abrasive grit should be spattered or run onto the parts below the lower lapping head, the construction shown effectively bars its passage to the interior of sleeve 14 and hence upper bearing 22 or lower bearing 18.

While the invention is illustrated in the case of apparatus particularly designed for the lapping of quartz oscillator plates, it will be clear to those skilled in this art that the construction shown, or modifications thereof, is useful for other purposes.

Having thus set forth the nature of my invention, what I claim is:

1. In apparatus of the character described, the improvement comprising a rotatable spindle connectible with a source of power, a sleeve mounted about the spindle, securing means to prevent rotation of the sleeve, a bearing between the sleeve and spindle, a bushing rotatably secured to the spindle at one end of the sleeve, a bearing-shield disposed exteriorly of and about the same end of the sleeve and a portion of the bushing, and a nut rotatably secured to the bushing and bearing-shield to provide a barrier against passage of foreign particles through the end of the sleeve to the bearing.

2. In apparatus of the character described, the improvement comprising a rotatable spindle connectible with a source of power, a sleeve mounted about the spindle, securing means to prevent rotation of the sleeve, a bearing between the sleeve and spindle, a bushing rotatably secured to the spindle at one end of the sleeve immediately adjacent the bearing to retain the same in position, a bearing-shield disposed exteriorly of and about the same end of the sleeve and a portion of the bushing, and a nut rotatably secured to the bushing and bearing-shield to provide a barrier against passage of foreign particles through the end of the sleeve to the bearing.

3. In apparatus of the character described, the improvement comprising a rotatable spindle connectible with a source of power, a sleeve mounted about the spindle, securing means to prevent rotation of the sleeve, a bearing between the sleeve and spindle, a bushing rotatably secured to the spindle at one end of the sleeve, said bushing being provided with an outwardly extending shoulder portion fitting within the sleeve immediately adjacent the bearing to retain the same in position, a bearing-shield disposed exteriorly of and about the same end of the sleeve and a portion of the bushing, and a nut rotatably se-

cured to the bushing and bearing-shield to provide a barrier against passage of foreign particles through the end of the sleeve to the bearing.

4. In apparatus of the character described, the improvement comprising a rotatable spindle connectible with a source of power, a sleeve mounted about the spindle, securing means to prevent rotation of the sleeve, a bearing between the sleeve and spindle, a bushing rotatably secured to the spindle at one end of the sleeve, said bushing being provided with an outwardly extending shoulder portion fitting within the sleeve immediately adjacent the bearing to retain the same in position, a bearing-shield disposed exteriorly of and about the same end of the sleeve and a portion of the bushing, said bearing-shield being provided with an inwardly extending annular portion engaging said outwardly extending shoulder portion of the bushing, and a nut rotatably secured to the bushing and bearing-shield to provide a barrier against passage of foreign particles through the end of the sleeve to the bearing.

5. In apparatus of the character described, the improvement comprising a rotatable spindle, a stationary sleeve about said spindle, said sleeve internally threaded at one end, bearing means in the end portions in the sleeve and between the sleeve and spindle, a bushing including a portion extending along said spindle and a radial portion threaded into said end of the sleeve and retaining the bearing means therein, a bushing at the other end of the sleeve and including a portion fixed to and extending longitudinally of the spindle and a radially extending portion entering the sleeve and retaining the bearing means in place therein, a bearing shield at the last-mentioned end portion of said sleeve, and said shield including a cylindrical portion disposed about said end portion of the sleeve and an inwardly directed portion disposed against the outer side of the radially extending portion of the second-mentioned bushing and threaded to the portion of said bushing extending longitudinally of the spindle.

6. In apparatus of the character described, the improvement comprising a rotatable spindle, a stationary sleeve about said spindle, said sleeve internally threaded at one end, bearing means in the end portions in the sleeve and between the sleeve and spindle, a bushing including a portion extending along said spindle and a radial portion threaded into said end of the sleeve and retaining the bearing means therein, a bushing at the other end of the sleeve and including a portion fixed to and extending longitudinally of the spindle and a radially extending portion entering the sleeve and retaining the bearing means in place therein, a bearing shield at the last-mentioned end portion of said sleeve, and said shield including a cylindrical portion disposed about said end portion of the sleeve and an inwardly directed portion disposed against the end of the sleeve and the outer side of the radially extending portion of the second-mentioned bushing and fixed to the latter.

7. In apparatus of the character described, the improvement comprising a vertically disposed rotatable spindle, a vertical stationary sleeve about said spindle, bearing means in the upper end portion of the sleeve and between the sleeve and said spindle, a bushing fixed to the spindle at the upper end of said sleeve, said bushing including a portion extending longitudinally of and fixed to the spindle and a radially extending

portion entering the sleeve and retaining the bearing means in place, a bearing shield about the upper end portion of said sleeve and said shield including a cylindrical portion disposed about said end portion of the sleeve and an inwardly directed portion disposed against the outer side of the radially extending portion of the bushing and threaded to the portion of the bushing extending longitudinally of the spindle.
